UNITED STATES PATENT OFFICE.

JAMES J. COOPER, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

RAILWAY-CAR END.

1,208,915.

Specification of Letters Patent. Patented Dec. 19, 1916.

Application filed November 6, 1913. Serial No. 799,516.

To all whom it may concern:

Be it known that I, JAMES J. COOPER, a citizen of the United States, residing in the city of St. Louis, State of Missouri, have 5 invented a certain new and useful Improvement in Railway-Car Ends, of which the following is a full, clear, and exact description, such as will enable others skilled in the art to which it appertains to make and use the 10 same, reference being had to the accompanying drawings, forming part of this specification, in which—

Figure 1 is an elevational view of a car end of my improved construction. Fig. 2 is 15 a side elevational view of a car end of my improved construction, the same applied to a car. Fig. 3 is a vertical section taken approximately on the line 3—3 of Fig. 1. Fig. 4 is an end elevational view of a modified form of my improved car end. Fig. 5 20 is a side elevational view of the end portion of a car which is equipped with the modified form of end. Fig. 6 is an enlarged detail sectional view taken approximately 25 on the line 6—6 of Fig. 1 and showing the construction of the joint between two of the sections of my improved car end. Fig. 7 is an enlarged detail section taken approximately 30 on the line 7—7 of Fig. 1, and showing a preferred form of the means employed for attaching the car end to the uprights or posts of the car frame.

My invention relates generally to railway cars and more particularly to the construction 35 of the car end walls.

In railway cars and particularly those designed for, and used in freight service, the end portions of the car body and the end walls, are subjected to severe stresses and 40 strains resulting from service shocks and vibrations and by reason of the sudden starting and stopping of the cars and the shifting of the lading or contents thereof.

The principal object of my invention is to 45 construct a car end wall from a plurality of sections of material, preferably sheet metal, each section being reinforced and stiffened, if desired, by ribs or corrugations which are pressed in the sheet metal, and to 50 provide on the car end wall so formed, one or more hollow reinforcing and stiffening members having certain characteristics. These reinforcing and stiffening members

are formed at the joints between the sections of sheet metal of which the car end is formed, the conjoined edges of the metal 55 sections being bent to proper shape and united by means of a joint member such as a commercially rolled metal shape, to form a beam in the nature of a box girder.

My improved construction provides a comparatively simple, inexpensive car end, which can be readily combined with an ordinary car underframe and superstructure, and said end being materially stiffened and reinforced both horizontally and vertically will be very 60 effective in resisting such stresses as may arise from shifting loads, ordinary service shocks and vibrations or collisions.

With the above and other objects in view, my invention consists in certain novel features of construction and arrangement of parts, hereinafter more fully described and 70 claimed.

As illustrated in the accompanying drawings and particularly Figs. 1, 2, and 3, the 75 car end is composed of a pair of sheet metal plates or sections 1 and 2, each of which is formed with a series of vertically disposed stiffening ribs or corrugations 3. These ribs or corrugations are preferably arranged 80 parallel with each other and are formed in the sheets of metal in any suitable manner, preferably by means of dies. The ends of the sections 1 and 2 are bent at right angles to the plane occupied by the main body portions 85 of said sections as designated by 4, and said bent ends are attached in any suitable manner to the end portions of the side walls of the car. The upper edge of the upper section 1 is preferably attached directly to the top plate of the car end structure and the bottom portion of the lower section 2 is attached in any suitable manner 90 to the end sill of the car underframe. The lower portion of the upper section 1 overlies the upper portion of the lower section 2, and this overlying lower portion is bent outward and downward as designated by 5. Arranged between the lower edge of the outwardly and downwardly bent portion 5 and 95 the adjacent portion of the lower plate 2, is a transversely disposed rail or bar 6, preferably a rolled shape such as a Z-bar, and where such shape is used, the upwardly projecting flange is attached in any suitable 100 105

manner to the lower edge of the portion 5 and the depending flange is attached directly to the upper portion of the plate 2. The extreme upper edge of the section 2 lies immediately beneath and is fixed to that portion of the section 1 which is immediately above the outwardly and downwardly bent portion 5, and thus said portion 5, the joint member 6 and that portion of the section 2 immediately behind said portions 5 and 6, form a horizontally disposed transversely extending tubular member or box girder, which materially strengthens and reinforces the central portion of the end wall.

15 The disposal of the edge of the joint member between the overlapped edges of the sections prevents the entrance of water behind the joint member, and protects the joint member from possible blows which 20 would tend to tear it loose from the plates.

It will be understood that a piece of sheet metal bent to proper shape may be utilized in place of the rolled shape 6 and also that a shape other than a Z-bar can be utilized 25 as the joint member between the main sections of the car end.

In Figs. 4 and 5 I have shown a car end formed of three main sections or sheets of metal and where such construction is employed, a pair of box girders or tubular stiffening and reinforcing members are formed at the joints between the sheets of sections of metal.

30 The sides of my improved car end are tied to the transom posts of the car body by means of bolts 8, the inner ends of which are fixed in any suitable manner to the transom posts. The outer ends of these bolts extend through the end portions of the 40 sheets 1 and 2 and receive nuts, or like fastening devices. (See Fig. 7). In case the plates forming the end wall are joined on vertical instead of horizontal edges, it is obvious that this structure will provide vertical 45 stiffening members extending longitudinally of the plates.

A car end of my improved construction is 50 comparatively simple, can be easily and cheaply manufactured, and by overlapping edges of the sections of material of which the car end is formed, and arranging between said edges a suitable joint member, a reinforcing member in the form of a box girder is provided, which materially reinforces and strengthens the car end and causes all internally and externally applied 55 shocks and blows and all service strains and vibrations to be transmitted directly to framing portions of the car body or under-frame structure.

60 It will be readily understood that minor changes in the size, form and construction of the various parts of my improved car end may be made and substituted for those herein shown and described, without departing

from the spirit of my invention, the scope of which is set forth in the appended claims.

I claim:

1. A car end comprising a plurality of sections of sheet metal, the lower edge of 70 one of which sections overlaps the upper edge of the adjacent section, and a joint member interposed between the overlapping edges of said sections, portions of which overlapping portions combine with said 75 joint member to form a transversely disposed box girder.

2. In a car end, a pair of sections of sheet metal arranged so that the edge of one section overlaps the edge of the other 80 section, and a joint member having a portion interposed and secured between said overlapping edges, a portion of which joint member cooperates with portions of the sections to form a transversely disposed box 85 girder.

3. In a car end, a pair of conjoined sections of sheet metal the upper one of which has its lower edge offset with respect to the lower section and overlapping said lower section on the exterior thereof, and a joint member extending longitudinally of the sections and having its upper edge disposed behind the offset edge of the upper section and secured thereto, and its lower edge secured to the lower section below the upper section, said joint member having portions disposed in front of the plane of said sections so as to form a beam for stiffening the end structure. 90

4. The combination in a car end, of two corrugated plates, one located above another; a downwardly extending flange at the lower edge of the upper plate and an upwardly extending flange at the upper edge of the lower plate, the flange of the lower plate being out of line with the flange of the upper plate; and a Z-beam, the upper flange of the Z-beam being connected 95 to the flange at the lower edge of the upper plate and the lower flange of the Z-beam being connected to the flange at the upper edge of the lower plate. 100

5. The combination in a car end of two sheet metal wall sections one located above the other, the upper section having a lower marginal flange overlapping and offset from the upper margin of the lower section, and a bar member extending longitudinally of the sections along their juxtaposed margins and having a longitudinally extending upper flange connected to the flange at the lower edge of the upper plate and another longitudinally extending flange connected 110 to the lower section. 115

6. The combination in a car end of two wall sections one located above the other, the upper section having a downwardly extending flange at its lower edge, and the lower section having an upwardly extend- 120 125 130 135

ing flange at its upper edge disposed out of line with the flange of the upper section, and a stiffening member having a longitudinally extending upper flange connected to the flange of the upper section and a second longitudinally extending flange connected to the flange of the lower section.

In testimony whereof I hereunto affix my signature in the presence of two witnesses, this third day of November, 1913.

JAMES J. COOPER.
